UNITED STATES PATENT OFFICE.

JOHN F. KOEBEL, OF BUFFALO, NEW YORK.

VALVE-LOCK FOR AUTOMOBILES AND THE LIKE.

1,348,364.

Specification of Letters Patent.

Patented Aug. 3, 1920.

Application filed April 14, 1919. Serial No. 289,942.

To all whom it may concern:

Be it known that I, JOHN F. KOEBEL, a citizen of the United States, residing at Buffalo, in the county of Erie and State of New York, have invented new and useful Improvements in Valve-Locks for Automobiles and the like, of which the following is a specification.

This invention relates more particularly to devices for preventing the theft of automobiles, the same belonging to the class comprising a cut-off valve located in the fuel-feed pipe of the carbureter and a suitable lock for said valve under the control of the owner of the car or other authorized person. The locking device is however equally applicable to the corresponding valve of a motor boat, as well as various other valves liable to be tampered with by unauthorized persons.

The object of my invention is the provision of a strong and reliable valve-lock of this character which is simple, light and compact in construction and which can be produced at comparatively small cost.

In the accompanying drawings:

Figure 1 is a front view of the lock applied to the feed pipe of a carbureter. Fig. 2 is a side elevation of the parts. Fig. 3 is an enlarged vertical section of the lock on line 3—3, Fig. 2. Fig. 4 is a horizontal section on line 4—4, Fig. 3, showing the valve unlocked and open. Fig. 5 is a similar section showing the valve locked in its closed position.

Similar characters of reference indicate corresponding parts throughout the several views.

10 indicates the float-chamber of an ordinary carbureter and 11 the usual fuel feed pipe leading thereto. This pipe contains a cut-off valve 12 of any suitable construction for shutting off the supply of fuel to the carbureter when the automobile is parked or left where it is liable to be stolen. In the preferred construction shown, the valve has the conventional rotary plug 13 terminating in a square or flat-sided stem 14. The valve-case has integral branches 15, one of which has a union 16 for coupling it to said feed pipe 11, while the other is connected with the float chamber by an elbow 16^a, or other suitable connection.

A strong metallic box or housing 17 of rectangular or other suitable form incloses the valve 12 and the lock hereinafter described.

This box is closed by a cover 18 which is secured in place by suitable fastenings, such as screws 18^a having their heads located at the back of the box where they are difficult of access when the box is placed with its back toward the engine of an automobile, for example. The box is provided in its sides with openings 19 for the passage of the pipe-branches 15, these openings being formed partly in the body of the box and partly in the cover.

Applied to the square stem of the valve-plug is an operating lever 20 for opening and closing it, the lever having a corresponding opening 21 for receiving said stem. The lever extends through a horizontal slot 22 formed partly in the cover of the housing and partly in one of its side walls. This slot is of the proper length to permit the lever to be turned from the closed position of the valve shown in Figs. 1, 2 and 5 to the open position shown in Figs. 3 and 4, the ends of the slot forming stops for the lever which predetermine the open and closed positions of the valve. In addition to the opening 21, the lever is provided in its inner portion with a locking loop or aperture 23 adapted to receive the bolt 24 of a lock 25 having the usual guide 25^a for the bolt, the preferred lock shown in the drawings being of the well-known cylinder type operated by a flat key, although any other appropriate lock may be used, if desired. As shown, the cylindrical portion of the lock extends through an opening 26 in the cover. The locking aperture 23 of the lever is preferably in the form of a transverse slot or loop of the proper dimensions to fit the locking-bolt as closely as practicable, the slot being arranged to register with the bolt when the lever is turned at right angles to the feed pipe 11 to close the valve, and said bolt being movable parallel with the axis of the valve.

To lock the valve, the lever is turned to the position just mentioned, after which the bolt is projected into the loop of the lever by the use of a proper key. Under these conditions, unauthorized persons will find it impossible to turn on the gasoline-supply and operate the car. Upon unlocking the lever by the withdrawal of the lock-bolt, the lever can be freely turned to open the valve and admit fuel to the carbureter.

By providing the lever with such a locking loop or aperture, a very strong connec-

tion is obtained between the lever and the bolt of the lock on account of the large contact surface between the parts. It will be observed that if it be attempted to turn the locked lever out of that position, its loop will bear against the bolt at diagonally opposite points, and as the loop is closed on all sides it possesses the necessary strength to withstand such strains.

10 As the valve-stem, as well as the valve, is wholly within the box, it is inaccessible and cannot be operated, except by the lever when unlocked. The several parts, including the lock, are all inclosed in a single box or housing, and as this unitary box is located under the automobile hood adjacent to the carburetor, it is exceedingly difficult for unauthorized persons to tamper with the lock without attracting attention and running great risk of detection.

15 As the rectangular base-portion 25^a of the cylinder-lock is relatively thin or shallow, the upper part of the box may be made shallower than the lower part containing the valve, as shown. This reduces the weight of the device and renders it more compact.

20 Aside from being strong and reliable, this lock has the advantages of lightness, simplicity of construction and low cost.

25 30 The construction shown has the further advantage that it does not require a special

valve but permits the use of a standard or stock-valve which can be readily renewed when worn out without requiring replacement of the entire device.

I claim as my invention:

1. The combination of a housing, a valve-case separate from said housing, a valve in said case having a stem, an operating lever for said stem arranged adjacent to said valve and extending through the wall of said housing, and a lock having a locking bolt movable parallel with the axis of said valve to engage said lever, said valve and said lock being both located within said housing.

2. The combination of a valve-case having oppositely-extending branches, a unitary housing inclosing said valve-case and having openings in its walls for the passage of said branches, a valve in said case having a stem, an operating lever applied to said stem and extending through the wall of said housing, and a lock arranged above said valve and having a locking bolt movable parallel with the axis of said valve to engage said lever, said valve, said lock and the part of said valve-stem between the valve and the lock being located wholly within said casing.

JOHN F. KOEBEL.
